The ornamental design for a light source for printer as shown and described.

DESCRIPTION

FIG. 1 is a front-right-top view of a light source for printer according to my new design;

FIG. 2 is a rear-left-top view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The oblique shading in the drawings illustrates translucency. The broken line showing portions of the light source for printer form no part of the claimed design.
